SIGNAL LIGHT SUPPORT

Henry Koch, Jamaica, N. Y., assignor to Dictograph Products Company, Inc., New York, N. Y., a corporation of Delaware

Application August 11, 1932, Serial No. 628,290

2 Claims. (Cl. 177—329)

This invention relates to supports for incandescent lights and, more particularly, to such supports adapted for the support and connection to electrical circuits of small incandescent light bulbs or lamps frequently used as signal lights in telephone switch-boards and the like.

A general object of the invention is the provision of such a device which can be readily and economically manufactured, will efficiently support and make the necessary electrical connections with an incandescent light bulb and which allows ready mounting and demounting of the light bulb with respect to the support.

A more specific object of the invention is the provision in such a device of a pair of resilient metallic members to grip the sides of the base of the light bulb and to make electrical contact therewith and a centering device to engage the central button of the base of the bulb and make electrical contact therewith, all of which cooperate with means to support the tip of the bulb efficiently to support and provide the necessary electrical connections for the incandescent light in a manner to allow its ready mounting and demounting; such structure being simple and rugged and requiring a minimum cost in production.

A further object of the invention is the provision in such a device of a U-shaped metallic clip adapted to grip the sides of the base of the light bulb and a spring finger interposed between the arms of the U-shaped clip and having an indentation adapted to receive and center the central button of the base of the bulb.

Other objects of the invention will in part be obvious and will in part appear hereinafter.

The invention accordingly comprises the features of construction, combination of elements and arrangement of parts, which will be exemplified in the construction hereinafter set forth and the scope of the application which will be indicated in the claims.

For a fuller understanding of the nature and objects of the invention reference should be had to the following detailed description taken in connection with the accompanying drawing, in which:

Fig. 1 is a top plan view, with parts in section, of the device of the present invention showing an incandescent light bulb supported thereby;

Fig. 2 is a view on line 2—2 of Fig. 1, partly in section and partly in elevation;

Fig. 3 is an elevational view of the structure depicted in Figs. 1 and 2;

Fig. 4 is an elevational view of a panel with

parts broken away showing the bulb-tip support and mounting clip of the present device mounted thereon.

Fig. 5 is a sectional view on line 5—5 of Fig. 3, looking in the direction of the arrows.

Referring to the drawing like numerals denote like parts throughout. A panel 10 of a device in which a signal light is desired, such as a telephone switch-board, is provided with a visual aperture 11. Opposite the aperture 11 is disposed a bulb-tip support 12 formed from any suitable material, such as sheet metal, and provided with a centrally disposed cup-shaped portion 13 adapted to receive the tip of a light bulb 14. The bottom of the cup-shaped portion 13 is preferably cut out as shown to allow visibility of the light through the aperture 11 in the panel 10. The bulb-tip support 12 is provided with a pair of oppositely disposed ears 15—15 to aid in the mounting of the bulb-tip support 12. A clip member 16 is provided with a pair of fingers 17—17 spaced apart a sufficient distance so that the body of the bulb-tip support 12 may be seated therebetween with the fingers 17—17 engaging the ears 15—15. The clip member 16 is secured to the panel in any suitable manner such as by a screw 18. When the clip member 16 is mounted in position on the panel the bulb-tip support 12 can be readily mounted thereon by slipping the ears 15—15 beneath the fingers 17—17.

Directly opposite the structure described above is mounted a bulb-base support 19 including a base 20, preferably of insulating material and mounted in any suitable manner on a supporting bracket 21. A centering spring finger 22 is mounted upon the base 20 in any suitable manner and is provided with a portion 23 having a face substantially perpendicular to the axis of the light bulb 14. This face is provided with an indentation 24 adapted to receive and center the central button 25 of the base of the light bulb 14. A pair of spring arms 26—26 are additionally mounted upon the base 20 and disposed on opposite sides of the spring finger 22. The arms 26—26 are of sufficient length and are shaped to engage and grip opposite sides of the light bulb base 27. In the preferred form, the spring arms 26—26 constitute parts of a U-shaped clip insulated from the spring finger 22 by an insulating washer 28 and held in position on the base 20 together with the spring finger 22 by a transfixing bolt 29 threaded into the bracket 21 as shown in Fig. 2.

Electrical connection with the light bulb 14 is made by spring arms 26—26 acting as one circuit terminal and the spring finger 22 acting as the

other circuit terminal. The resilience of the spring finger 22 and the spring arms 26-26 allow ready and secure mounting of the light bulb 14, the cup-shaped portion 13 of the bulb-tip 5 support 12 cooperating with the indentation 24 of the spring finger 22 to properly position the light bulb 14.

It will thus be seen that the device of the present invention efficiently attains the objects set 10 forth above.

Since certain changes may be made in the above construction and different embodiments of the invention could be made without departing from the scope thereof, it is intended that all 15 matter contained in the above description or shown in the accompanying drawing shall be interpreted as illustrative and not in a limiting sense.

It is also to be understood that the following 20 claims are intended to cover all of the generic and specific features of the invention herein described, and all statements of the scope of the invention which, as a matter of language, might be said to fall therebetween.

25 Having described my invention, what I claim as new and desire to secure by Letters Patent, is:

1. In an incandescent light bulb support the combination with a panel having a visual aperture therein, of bulb-tip supporting means 30 mounted on said panel to support the tip of a signal light bulb in substantial alignment with the visual aperture and permitting light to pass from the bulb through the aperture, a pair of

spaced apart spring arms adapted to grip the sides of the base of the bulb, a resilient central bulb contact engaging means disposed between said spring arms, common means for supporting said spring fingers and said central bulb contact 5 engaging means in substantial alignment with the visual aperture including means to insulate said central bulb contact engaging means from said spring arms, a circuit terminal connected to one of said spring arms, and another circuit terminal connected to said central bulb contact engaging means.

2. In an incandescent light bulb support the combination with a panel having a visual aperture therein, of an apertured socket mounted on said panel to support the tip of a signal light bulb, the aperture in said socket being in substantial alignment with the visual aperture to permit light to pass from the bulb through the visual aperture, a U-shaped metallic spring clip adapted 20 to grip the sides of the base of the bulb, a spring finger having a portion projecting between the arms of said clip provided with an indentation to receive the central contact of the base of the bulb, common means supporting said clip and said 25 spring finger with the clip arms and indentation in said finger in substantial alignment with the visual aperture including means to insulate said finger from said clip, a circuit terminal connected to said clip, and another circuit terminal 30 connected to said finger.

HENRY KOCH.
